COMBINATION GARMENT

Flora Ellinger, Milwaukee, Wis.

Application April 29, 1937, Serial No. 139,679

1 Claim. (Cl. 2—77)

This invention relates to improvements in combination garments, and more particularly to a man's garment wherein an upper garment, as a shirt, carries integral depending portions arranged to form trunks or "shorts" so that the entire structure provides a unitary shirt and trunk garment.

Heretofore men's shirts have been provided with tail portions adapted to be tucked into the trousers and entirely independent of underwear or inner garments. With this arrangement, wearers engaged in athletics or work requiring vigorous movements, have been subjected to the annoyance of having the tail portions of the shirts pull out from the trousers.

It is, therefore, one of the objects of the present invention to overcome the above objection by providing a shirt having tail portions which are secured together in a manner so as to prevent upward shifting or pulling out of the tucked in portions of the shirt.

Another object of the invention is to provide a shirt having tail portions arranged to form integral trunks with overlapping lateral extensions for securing at the crotch whereby to form, with the shirt proper, a unitary article of wearing apparel.

A further object of the invention is to provide a combination shirt and trunk structure which is semi-form fitting whereby bulkiness and bunching of portions of the garment is eliminated.

A further object of the invention is to provide a combination shirt and trunk structure having a fashioned upper shirt portion, fashioned integral lower trunk portions, and adjacent lateral extensions on the latter portions which are adapted to be secured together in overlapping relationship to form a full crotch area which insures comfort and freedom of movement without undue pull on any portions of the garment.

A further object of the invention is to provide a combination garment having complementary opening flaps which will maintain their normal closing relationship during wear and require a minimum of buttons or other fastening means.

A further object of the invention is to provide a combination garment of the character described which is of very simple construction, which is strong and durable, is comfortable to the wearer and convenient to arrange, which is inexpensive to manufacture, and which is well adapted for the purposes set forth.

With the above and other objects in view, the invention consists of the improved combination

garment, and its parts and combinations as set forth in the claim, and all equivalents thereof.

In the accompanying drawing in which the same reference characters indicate the same parts in all of the views:

Fig. 1 is a view showing the combination garment as arranged and secured on a wearer;

Fig. 2 is an enlarged view of the garment with the trunk portions and crotch flaps separated and unsecured;

Fig. 3 is an enlarged fragmentary view of the lower rear portion of the garment; and

Fig. 4 is an enlarged detail sectional view through the front and rear crotch portions of the garment.

While the invention has been shown and described herein as being specifically applied to a particular form of man's shirt, it is not intended to limit the scope by such specific embodiment, and it should be understood that the improved features are readily applicable generally to other types of garments, sweaters, blouses, and the like.

Referring to the drawing, the shirt illustrated includes the usual body covering front sections 9 and 10 having adjacent edge portions adapted to be secured together by suitable means, as buttons 11. Sleeves 12 are attached at opposite upper side portions of the body sections and the top portion of the garment is provided with a collar 13.

The invention resides particularly in the construction of the lower portion of the garment, and the shirt, below the usual waist line, is formed with a pair of depending leg or trunk portions 14 and 15 which, at their ends, are of circular or tubular formation. Somewhat above the lower ends of the trunk portions and at the inner side of each of the same, there are a pair of complementary lateral extensions or plackets 16 and 17. Each of said plackets is of looped formation and the upper end of the rear extent of the placket 16 joins the upper end of the rear of the shirt body 22 at about the waist line in underlapping relation to the upper end of the rear extent of the placket 17 which joins the rear of the shirt body at the same place.

As is shown most clearly in Fig. 2, the front extent of the placket 16 terminates at its upper end integrally with the adjacent portion of the shirt section 9. Similarly, the upper end of the front extent of the placket 17 joins the shirt section 10. During normal wear, the entire placket or extension 17 overlaps the entire placket or extension 16, and the parts are re-

leasably secured in this relationship by a minimum of fastening means which, in the present exemplification, includes an upper front button 18 and a lower button 19 on the front extent 5 of the placket 16 adapted to pass through button holes 21 on the placket 17, and the rear portions of said plackets may be held in position by a rear button 25. Normally, said overlapping parts are arranged as shown in Figs. 1, 3 and 4 10 and provide for a closed crotch area, both forwardly and rearwardly, which has sufficient fullness to prevent binding and which is actually segregated from the trunk portions. By releasing one or more of the fastening means, said plackets may be spread and disengaged, both 15 forwardly and rearwardly, as in Fig. 2.

The rear of the shirt body on its inner surface and about at the waist line carries an elastic strap or belt 23. This belt is of sufficient length 20 to engage the rear and sides of the waist of the wearer and serves to hold the shirt body to the wearer and retards upward shifting of the same. The belt is removably held to the interior of the rear of the shirt body by oppositely disposed 25 buttons 24.

In use, the shirt is donned by opening the buttons 11 on the shirt body front sections and the wearer then inserts his legs into the trunks 14 and 15 and thereafter inserts his arms into the 30 shirt sleeves and then secures the shirt sections together in the usual manner. When the improved garment is worn and secured as described and shown, it is obvious that in addition to the shirt or upper garment member, integral lower 35 trunks are provided which serve as a lower under-garment. This garment is especially advantageous for workmen or persons who move and exercise considerably, as the danger of the shirt pulling out of the trousers at the waist is en-

tirely eliminated. The garment maintains an attractive appearance and has no undue bulkiness, but does provide for comfort and eliminates binding at the crotch. Also, the trunk plackets are arranged so as to normally remain in closed, 5 overlapping position, and a minimum of fastening means therefor are required. The combination garment is inexpensive to manufacture, is of simple and novel construction, and is well 10 adapted for the purposes set forth.

What is claimed as the invention is:—

A combination garment of woven inelastic material, comprising a top, outer-wear member of jacket-like structure with the edges of the front sections meeting in overlapping relationship, a line of securing means for said overlapping edges, an elastic belt detachably mounted within the rear and side portions of said top member adjacent the waist line thereof, separated trunk sections for inner wear integral with 20 and depending from said top member, a crotch placket secured to an inner upper side portion of each trunk section, said plackets being secured at their rear upper ends to a common portion of the rear of the top member adjacent its junction with the trunk sections and each placket being secured at its upper front end to separated portions of the front of the top member, the major portions of said plackets extending in 25 looped overlapping relationship between said 30 trunk sections, and pairs of securing means, laterally offset to one side of the line of securing means for the top member, for releasably holding said plackets together in closed overlapping condition, said belt contracting the lower rear portion of the garment and aiding in maintaining the rear portions of the plackets in closed condition.

FLORA ELLINGER.
